UNITED STATES PATENT OFFICE.

DANIEL N. SONERIN, OF CHICAGO, ILLINOIS.

DESIGN FOR A SHOE.

46,625.

Specification for Design.

Patented Nov. 3, 1914.

Application filed August 8, 1914. Serial No. 855,924. Term of patent 3½ years.

To all whom it may concern:

Be it known that I, DANIEL N. SONERIN, a subject of the Emperor of Austria-Hungary, who has declared his intention of becoming a citizen of the United States, residing at Chicago, in the county of Cook and State of Illinois, have invented a new, original, and ornamental Design for Shoes, of which the following is a specification, reference being had to the accompanying drawing, forming a part thereof.

The figure is a perspective view of a low shoe or slipper showing my new design.

I claim:

The ornamental design for a shoe as shown.

In testimony whereof I have signed my name to this specification in the presence of two subscribing witnesses.

DANIEL N. SONERIN.
